UNITED STATES PATENT OFFICE.

ALFRED F. SMITH, OF INGOMAR, PENNSYLVANIA.

COMPUTING ATTACHMENT FOR TYPE-WRITERS.

1,099,725.

Specification of Letters Patent.

Patented June 9, 1914.

Application filed May 6, 1913. Serial No. 765,794.

To all whom it may concern:

Be it known that I, ALFRED F. SMITH, a citizen of the United States, residing at Ingomar, in the county of Allegheny and 5 State of Pennsylvania, have invented certain new and useful Improvements in Computing Attachments for Type-Writers, of which the following is a specification.

My invention has in view to provide a 10 computing attachment for typewriters, adapted to operate in connection with the standard construction employing usual printing type, shifting carriage, operating keys, etc., and is designed to provide a 15 mechanism of this character of simple, accurate and efficient construction which will automatically and successively compute the several amounts printed, giving final results, either in addition or subtraction, success- 20 sively for each operation and for the final result by a visible indicator.

My invention embodies improvements, in 25 a calculating or computing machine, particularly adapted to embodiment in a type- writer, in providing a right hand and left hand "totaler," novel means for actuating a series or bank of indicating wheels through an internal shifting master pinion, means for transmitting rotating movement to the 30 master wheel through a slotted sleeve, rack and pinion mechanism for said sleeve, shifting gear mechanism for effecting engagement and disengagement between the rack and pinion mechanism, lost motion gearing 35 between the actuating lever key of the machine and the rack and pinion mechanism, clutch mechanism dependent on the motion of the typewriter carriage for connecting and disconnecting the transmission shaft of 40 the rack actuating gearing, locking and unlocking mechanism for the actuating key segmental gears, together with the several features of improvement and construction as more fully hereinafter set forth and 45 claimed.

In the drawings illustrating the invention, Figure 1 is a view of the typewriting machine provided with my improvement, in front elevation. Fig. 2 is a plan view of a 50 portion of the machine, showing the attachment. Fig. 3 is an enlarged sectional view, showing indicating disks and the operating mechanism in elevation. Fig. 4 is a vertical sectional view through the indicating 55 disks, illustrating the arrangement of the longitudinal adjustable positioning shaft

for the actuating master pinion, the section being taken on the line IV. of Fig. 5. Fig. 4^a is a detail view showing the spring retracted gear shafts. Fig. 5 is a cross sectional view taken on the line V. V. of Fig. 3. Fig. 6 is a plan view in detail, showing a portion of the actuating mechanism by which movement is imparted to the rack bar operative mechanism. Fig. 7 is a detail view in elevation, illustrating the clutch mechanism, etc. Fig. 8 is a cross sectional view taken on the line VIII. VIII. of Fig. 3. Fig. 9 is a detail cross sectional view, showing two of the co-acting pinions. Fig. 10 is a detail view, showing the arresting device. Fig. 11 is a perspective detail view showing the actuating arm for the rack bar mounted on the marginal stop of the scale bar. Figs. 12, 13 and 14 are detail views 75 showing reversing mechanism for the rack controlling the operation of the master pinion for either addition or subtraction. Fig. 15 is a perspective detail view, showing the clutch operating lever mechanism. Fig. 16 80 is a detail view showing the cam controlling locking mechanism for the segmental gears and the rack shaft. Fig. 17 is a similar view showing one of the rack bars and its actuating gear. Fig. 18 is a similar view 85 showing one of the key-actuated gears depressed and the relative position of its co-acting gear, in lost motion position. Fig. 19 is a detail view showing a duplicate cam actuating arm. 90

The indicating mechanism for giving the results, either in addition or subtraction, comprises a group of indicating or "totaling" wheels *a* and *b* arranged at each side of the central portion of the machine within a surrounding partly cylindrical casing 2, having a corresponding series of sight apertures 3 for exposing the particular numeral of each wheel *a* or *b* to view, as it is actuated in connection with the operating mechanism, the several wheels of each series being revolvably mounted within intervening stationary housing rings 4, fixedly located and connected with the casing by any suitable means, as rods 5 (Figs. 3 and 4). 95

It will be understood that either group or series of wheels *a* or *b* is independent of the other, and is operative independently or alone, by its particular actuating rack, hereinafter described, dependent on individual 100 clutch mechanism, which is controlled by selective adjustable cam actuating devices 105

carried by the scale bar or a marginal stop thereon, and adapted to cooperate with the ordinary set of type bars of a standard machine. Inoperative or "dead" wheels a' and b' , corresponding to the decimal point position, and unprovided with indicating numerals, comprise an idler element of each series. Each of said wheels a and b is provided with a laterally off-set portion 6 providing annular space for interposing a projecting tooth 7 or teeth, in the case of the unit wheel, adapted to actuate the particular one of a corresponding series of toothed idler wheels 8, loosely mounted on shaft 9, and adapted to intermittently transmit movement from one wheel to the other to accomplish accumulation of the adding or subtracting process, in the well-known manner of mechanism of this type and which will be readily understood without further description, it being understood that the number of the wheels, the arrangement of the indicating numerals, etc., is such as to effect the maximum capacity of the invention within any desired limits. In the construction illustrated, the machine has a capacity to the extent of 9,999,999.99. Each of the wheels a and b is provided with an inner peripheral series of pinion teeth 10, registering longitudinally throughout the entire series, the endmost indicating wheels abutting against stationary terminal, non-acting wheels 11, 11, at each end, said wheels being located within and against the endmost walls 12, 12, forming portions of the framework and casing.

For the purpose of actuating the wheels a and b one at a time, I provide a longitudinally adjustable master pinion 13 which is mounted upon a rotatable sleeve 14 having transverse slots 15, 15, through each opposite side, with which sleeve the master pinion 13 is rotatably connected by means of a transverse pin 16, said pin extending also through the freely rotatable terminal 17 of the longitudinally shifting shaft 18. Said shaft, as shown, is provided with a series of annular rack teeth in engagement with the teeth of an actuating pinion 19 mounted on shaft 20 and which is actuated for shifting the shaft 18 forwardly or backwardly, depending upon the adjustable actuating mechanism, hereinafter described. The rotatable terminal 17 is connected with the shifting shaft 18, at each end by means of a ball joint 21, so constructed as to permit of free turning of the terminal 17 independent of the shaft and to provide for longitudinal movement of the terminal and master wheel 13 in either direction, by said shaft. The slotted sleeve 14 is rotatably mounted at each end in the casing frame 12, as shown, and each sleeve is provided at its inner end with an actuating pinion 22, secured upon the sleeve in any suitable manner, as by a key

23. Thus, each sleeve and its longitudinally adjustable master wheel when located in register with the particular indicating wheel which corresponds with the particular numerical column being printed on the typewriter, is designed to be actuated through its pinion 22 and the rack and gearing which are thrown into operative engagement by its particular clutch mechanism under control of the particular actuating arm and cam employed, mounted on the marginal stop and scale bar.

For the purpose of rotating sleeve 14 and master pinion 13 in one direction or the other, as desired, the mechanism illustrated in the drawings, and particularly in Figs. 12, 13 and 14, is provided, whereby to actuate the sleeve 14 to the desired extent, assuming the master wheel in engagement with one of the several indicating wheels a or b , dependent upon the carriage control shifting mechanism, hereinafter described, and which transmits its motion through pinion 19 to shifting shaft 18. Each pinion 22 is designed to be rotated in one direction or the other through either intermeshing pinion 24 or 25 carried on a stud 26 extending inwardly from a rocking bracket arm 27 which is pivotally hung around the outer end portion of each sleeve 14, as indicated at 27 (Fig. 4) between the casing wall 12 and pinion 22, at each side of the center of the machine, one such bracket with its pinions being provided for each pinion 22. Each of the pinions 24 and 25 is provided with a companion pinion 24' and 25' respectively, also rotatably mounted on studs 26 and normally pressed into holding engagement with its companion pinion 24 and 25 respectively by a coiled spring 28. The inner contacting faces of companion pinions 24-24' and 25-25' are provided with series of ratchet teeth 29, operable to interengage and impart motion from one companion pinion to the other in one direction, but allowing pinion 24' or 25' to rotate in reversed direction without imparting movement to its companion pinion 24 or 25, by riding over the wheels and being pressed backwardly thereby, compressing springs 28.

For the purpose of positively actuating either pair of wheels 24-24' or 25-25' upon downward motion of the particular key lever C of the machine which operates to print the particular numeral appropriate for the particular operation,—as in the ordinary functioning of the typewriter itself,—I provide the double sided rack bar 30 which is vertically and slidably mounted in a supporting guide or bracket 31, extending outwardly from the inner face of casing 2, which rack bar is bifurcated at its upper end, as shown, providing the terminal members 32, 33, each of which is provided across its outer edge with a series of rack teeth 34,

- 35, adapted to intermesh with the teeth of pinion 24' or 25', depending upon which pinion is thrown into mesh, for imparting rotation to sleeve 14 in the desired direction (Figs. 5, 12, 13, and 14). For the purpose of properly bringing one pinion or the other, 24' or 25', into operative meshing engagement with rack teeth 34 or 35, dependent upon whether addition or subtraction is being performed; or for throwing each pinion 24' and 25' at the same time out of engagement with either set of rack teeth 34 or 35 for inoperation, the bracket 27 is provided with a central depending lug extension 36 which is engaged by the clevis terminal 37 of a controlling lever 38 pivoted on supporting shaft or stud 39, extending downwardly through a slot 40 in the front casing 2 and provided with a finger terminal 41.
- 20 This device is adapted to be set in either the upper position (Fig. 5) for addition, or in the lower position (Fig. 14) for subtraction, or in the intermediate position (Fig. 13) for inoperative positioning of the pinions 24' and 25'. As shown in Fig. 1, these three positions are indicated by the denominating letters A, D and S. When lever 38 is thrown to the raised position, as in Figs. 5 and 12, the terminal 36 of bracket 27 is thrown inwardly, throwing pinion 24' away from engagement with rack teeth 34 and pinion 25' into engagement with teeth 35. When the lever is thrown to the intermediate position, (Fig. 13) both pinions 24' and 35 25' are out of engagement with the rack teeth 34 and 35; and when the lever 38 is thrown into the lowered position (Fig. 14), pinion 24' is brought into intermeshing engagement with rack teeth 34, and pinion 25' is still maintained out of engagement with teeth 35. If, therefore, the rack bar 30 is lowered when pinion 25' engages rack teeth 35, as in Figs. 5 and 12, pinions 25' and 25 will be rotated in the direction of the arrow, and will impart motion to pinion 22 in the direction of its arrow, rotating the sleeve 14 and master pinion 13 to an extent dependent upon the downward travel of rack bar 30. It is, therefore, desirable that the rack bar 50 shall be actuated only sufficiently far, for each key lever manipulation, to rotate the master wheel 13 to an extent corresponding to the movement necessary to bring the proper numeral into view, in conformity with the standard uniform printing action of the type bar and type, the movement of all of which is the same.
- For the purpose of actuating the rack bar 30, it is provided with a series of rack teeth 60 42 in meshing engagement with a segmental pinion 43, which is loosely mounted by its hub upon shaft 44 extending across the lower portion of the casing and adapted to be intermittently partially rotated for each operation, when the computator mechanism is being used (Fig. 17). It will be understood that segmental pinions 43 are in pairs, one for each rack bar 30 and the gearing for actuating each sleeve and master pinion, bank of indicating wheels *a* and *b*, as are the other connected parts above described, for the purpose of either adding or subtracting in two different columns, or for using either separately.
- For the purpose of actuating shaft 44 only 75 sufficiently, more or less, to effect the desired downward movement to rack bar 30, each particular operating key lever C is provided with a connecting rod 45 which in turn is connected with a segmental pinion 46 adapted to actuate a coacting mutilated pinion wheel 47 secured on shaft 44, (Fig. 8) a pair of wheels 46-47 being provided for each particular lever, there being ten in all of such, as shown, five at one side and five at the other, corresponding in number to the decimal number of the numerals comprising the complete set ordinarily used, the wheel 47 being omitted for the zero key. Each particular segmental gear 46 and 47 is 80 mounted upon its pivoting shaft 48 and 44 respectively and is provided with a hub 49 having a clearance slot 50 for lost motion engagement with a pin 51 extending outwardly from shaft 48, whereby any particular segmental gear 46 or 47, when lowered, will partially rotate shafts 48 and 44, but without imparting movement to any other of the segmental gears 46 or 47. Shafts 48 and 44 are normally retracted by any suitable spring device, as springs 48^a, 44^b, engaging arms 48^a, 44^b, secured to the shafts, as in Fig. 4^a, or by other suitable means.
- The purpose of the lost motion mounting 95 of gears 46-47 on shafts 48-44 is to primarily effect movement of the particular gear 46 acted upon, and its companion gear 47, and to at the same time actuate shaft 48 to effect locking of all of the other gears 46 and their connected parts, by means of a 100 latch 52 adapted to be lowered into a suitable locking notch 53 in the upper edge portion of each gear 46, as shown (Fig. 16.) For the purpose of lowering the latches 52 downward into said notches, a cam 54 is 105 mounted on shaft 48 and actuates a bell crank lever 55 pivoted at 56, the other end of the lever engaging underneath one of the latches 52 by a pin or lip 57 thereon, thereby throwing all of the latches upwardly on their pivoted mounting stem 58 when the cam 54 is inoperative, and allowing the latches to fall into notches 53 when the lever is thrown down by the cam. The cam 54 is so constructed as to maintain bell crank 110 lever 55 in thrust out position until the end of the operation, locking all of the gears 46 by the latches 52, ^{so} that only the particular gear being used is free to move. It will be understood that at the commencement of 115
- 120
- 125
- 130

the operation, the actuated gear 46 moves past the point of latch 52 slightly before cam 54 actuates the lever to allow the latches to make locking engagement with the remaining gears. At the same time that cam 54 operates lever 55, a locking bar 59 pivoted at 60 is thrust downwardly between the teeth of rack shaft 18 by a connecting rod 61, positively holding the rack shaft in locked position during the printing operation, and preventing its movement until the termination thereof.

It will be observed that the teeth of each particular gear 46 and 47 are limited in number to the desired extent of movement of gear 47, and these gears are so constructed as to prevent further movement of gear 47 during the continued further movement of gear 46 to the full extent of the uniform limit of the stroke of each particular key lever C. For the purpose of providing for lost motion ensuing after the desired movement of gear 47 is effected, the periphery of the gear is concaved immediately following the last operative tooth, as indicated at 62, conforming to the outer radius of gear 46, whereby said gear will slide past the gear 47 without affecting it on further downward movement, and will engage its teeth on the reverse movement to reestablish the normal position (Figs. 8 and 18). The positioning of the master wheel 13 longitudinally and with relation to the particular indicating wheel a or b to be actuated depends primarily on the travel of the carriage within a certain predetermined distance, during which it is desired to print the number, as in a column of figures. Adjustably mounted on the scale bar of the carriage, or on any other convenient portion thereof, is a suitable movable support, as the marginal stop 64 adapted to be set in any desired position longitudinally of the scale bar, as will be readily understood, and with the usual indicating pointer 65 for locating it with relation to the indicating pointer 65 for locating it with relation to the indicating scale of the bar.

The marginal stop 64 is provided with a dovetailed recess 66 between its endmost portions, into which recess is set the upper end of actuating arm 67 which extends downwardly in front of the track bar t behind the casing of the computing mechanism above described. The arm 67 is provided with a terminal 68 adapted to engage the shouldered terminal 69 of a latch 70 which is pivotally mounted in shifting rack bar 71. Said bar is slidably mounted in the rear upper portion of the case 2 and is provided with a series of rack teeth 72 along its underside in engagement with a pinion 73 mounted on the inner end of shaft 20 connected with a retracting spring 75 at its other end (Fig. 11). The shaft 20 extends through

the front of the case and is provided with an indicating hand 76 operable to indicate the position of shaft 20 and the corresponding position of the master pinion 13, on a dial 77 (Fig. 1). Another purpose of this feature is that by inserting a pin in any particular one of the holes 77' of the dial, providing an abutment for hand 76, its movement will be arrested and the limit of travel of shaft 18 also controlled so as to check the master pinion 13 at any desired point, for using the limited capacity only of the machine. The shaft 20 is also provided with a pinion 78 engaging a rack bar 79 mounted on a suitable slideway support in the front portion of the casing, as shown, and provided with a pointer 79' extending through slot 79'' and adapted to indicate the particular numeral corresponding to the wheel a or b with which the master pinion is in gear (Fig. 1). Mounted upon the middle portion of shaft 20 is the pinion 19 meshing into rack shaft 18 and adapted to shift it and the master wheels 13 in conformity with the extent of movement of the pinion 73, or controlled motion of shaft 20, under action of the sliding rack bar 71.

The forward end 69 of shouldered latch bar 70 is provided with a tapered or inclined nose, as shown, adapted to engage a pin abutment 80 as the travel of the carriage brings the latch bar to such point, where it is desired to disengage the actuating arm 67 therefrom to terminate movement of bar 71, abutment 80 thrusting latch 70 backwardly against a pressure spring 81, permitting the actuating arm 67 to travel along with the scale bar and marginal stop to the end of its movement. On the back travel, the other edge of the actuating arm 67 will ride over the latch end 69, depressing spring 81 and sliding by to the initial position, when it is ready for the next operation. The actuating arm 67 is designed, at the time it effects operation of pinion 73 and shaft 20 and its connected parts, to at the same time effect clutch engagement between shaft 44 and the hub of one of the rack actuating segmental pinions 43, or between shaft 44 and the hub of each of said pinions, depending on whether one or both series of indicating wheels are being used. For such purpose a clutch 82 is splined on shaft 44, one of such clutches being positioned at each side of the center and designed to transmit movement from shaft 44 through segmental pinion 43, depending on which of said pinions is clutched, and corresponding to the printing of one or more columns, whereby to operate one or the other of racks 30, depending on the setting of lever 38 for either addition or subtraction.

For the purpose of actuating clutch 82, I provide a clutch engaging clevis 83 at the lower end of a lever arm 84 pivoted at 85

to the inner side of the front wall of the casing, adapting it to swing in one direction or the other under the control of a bell crank lever 86. Said lever is pivoted at 87 on a 5 supporting cross bar 88, its long arm being connected with lever 84 at 88', and its short arm being connected at 89 with a connecting bar or link 90 which is connected at its other end at 91 with the lower end of the primary 10 actuating lever 92. Said lever is pivotally mounted on a rock shaft 93 supported within the casing and extends upwardly thereabove and is provided with an inwardly projecting terminal 94 adapted to be engaged by a cam 15 95 extending outwardly from the face of the lower portion of actuating arm 67 and having bevel ends or inclined terminals at each extremity, facilitating the engagement of said cam with the lever (Fig. 15). As actuating arm 67 is carried along by the marginal stop 64, as above described, cam 95 engages the end 94 of lever 92 and effects shifting operation of the lever mechanism and resulting clutch engagement of clutch 20 82 with the clutch hub of segmental pinion 43. Thereupon operation of any one of the several key levers C will impart downward movement to the particular rack bar 30 which it is designed to operate. When desired, both clutches 82 may be thrown into gear by the use of both levers 92 by the use of an actuating arm 67' having two cams 95 and 95' (Fig. 19), one of the levers 92 having its upper terminal 94' deflected over the 25 top of the other so as to engage said cam 95' at the same time as the other. It is also obvious that by use of an actuating arm and a properly located cam, either lever 92 may be individually actuated.

30 In order to prevent partial operation of any one of the segmental gears 46 and reaction thereof, should the key lever not be depressed to its limit, and in order to insure against reverse movement of shaft 48 in either direction, until its full travel has been accomplished, shaft 48 is provided with an arm 96 extending radially therefrom and provided with a centrally arranged finger 97, normally held within a receiving slot in 35 arm 96 in central position by means of a spring 98 at each side, whereby to permit of lateral movement of finger 97 in either direction against spring pressure. A segmental rack 99 is fixedly mounted by screws 100 to the framing and is provided with a series of ratchet teeth 101 along each side face, one series being opposed to the other in arrangement of their locking edges, and so disposed that, when shaft 48 is actuated to 40 50 55 60 65

ratchet teeth on the opposite face, interlocking with them in the same manner, until arm 96 has been retracted to its initial position (Fig. 10). As shown in Fig. 3, segment 99 is of sufficient inclination to the plane of movement of arm 96 as to deflect its extremities to one side and the other of such plane, so as to facilitate the operation and engagement of finger 97 and insure its locking co-action with the ratchet teeth. In riding along one side of the teeth downwardly, finger 97 will be gradually pressed back by the inclined arrangement of the contacting ratchet teeth, against pressure of spring 98 on one side, the same operation, in a reversed direction, being accomplished along the other side of the ratchet teeth.

The construction and operation of the invention will be understood from the foregoing description. The computing mechanism is applicable to any of the standard makes of typewriters and provides for the various computations ordinarily carried out in the use of typewriters in billing, writing statements, reports, etc., requiring additions or subtractions, or those computations usually provided for in special so-called adding machines. It is distinctive in providing the right hand and left hand totaler, each adapted to give its particular results, and serves as a check on the operation and results at all times. Thus, to illustrate: in the writing of remittance letters by banks, bank statement accounts, bank deposit sheets or voucher writing, the left hand totaler can be used to show the bank balance and the right hand totaler used for the purpose of adding the amounts of checks issued. By throwing the left hand totaler to operate in subtraction and the right hand in addition, the right hand totaler will give the total amount of the checks added successively, indicating each additional amount, while the left hand totaler will deduct the amount of each check from the balance.

In using the machine for daily charge billing in mercantile transactions, it can be used for writing and adding items charged in one totaler, while the other will carry the amount of items charged during the day. The machine can also be used for condensed charge billing, unit billing, and all systems of billing where a footing or checking of bills is done, also for listing of checks, and is adaptable for use on a typewriting machine for the purpose of addition or subtraction wherever any statement work of any description may be written on a typewriter.

What I claim is:

1. In computing mechanism of the class described, a series of indicating wheels having external indicating numerals and provided with internal teeth, exterior interengaging transmitting wheels, a longitudinally movable master pinion adapted to engage

- said indicating wheels individually, a slotted sleeve extending through the master pinion, means for rotating the slotted sleeve, a rack toothed thrust shaft, and a rotatable terminal thereon connected with the master pinion through the slotted sleeve.
2. In computing mechanism of the class described, a series of indicating wheels having external indicating numerals and provided with internal teeth, exterior interengaging transmitting wheels, a longitudinally movable master pinion adapted to engage said indicating wheels individually, and means for rotating the master wheel and its engaged indicating wheel embodying a rotatable slotted sleeve and a thrust shaft having a portion rotatably connected with the master pinion through said slotted sleeve.
3. In computing mechanism of the class described, a series of indicating wheels provided with internal teeth, exterior interengaging transmitting wheels, a longitudinally movable master pinion adapted to engage said indicating wheels individually, a rotatable slotted sleeve engaging the master wheel, and a longitudinally movable shaft having a rotatable terminal also engaging the master wheel.
4. The combination with a series of internally toothed indicating wheels and intervening motion-transmitting mechanism therefor, of a longitudinally adjustable interior master pinion, a thrust shaft therefor, and a surrounding slotted sleeve rotatably engaging the master pinion and provided with a terminal actuating gear.
5. The combination with a series of internally toothed indicating wheels and intervening motion-transmitting mechanism therefor, of a longitudinally adjustable interior master pinion, a thrust shaft therefor, a surrounding slotted sleeve rotatably engaging the master pinion and provided with a terminal actuating gear, and mechanism operable to actuate said terminal pinion in either direction.
6. The combination with a series of indicating wheels provided with intervening motion-transmitting gears, of a longitudinally adjustable master wheel provided with rotating mechanism, a double-sided rack bar, means for actuating the rack bar, and adjustable mechanism for transmitting movement from one side of said rack bar to the master pinion rotating mechanism, substantially as set forth.
7. The combination with a series of indicating wheels provided with intervening motion-transmitting gears, of a longitudinally adjustable master wheel provided with rotating mechanism, a double-sided rack bar, means for actuating the rack bar, adjustable mechanism for transmitting movement from one side of said rack bar to the master pinion rotating mechanism, and mechanism for adjusting the transmitting mechanism from the rack shaft to said parts, substantially as set forth.
8. The combination with a series of indicating wheels, master wheel, sleeve and its pinion; of a tilting frame provided with composite ratchet-toothed spring-pressed pinions, a vertically movable double-sided rack bar, means for actuating the rack bar, and means for adjusting said frame to throw said pinions into and out of gear, substantially as set forth.
9. The combination with a typewriter provided with indicating wheels, master pinion, thrust bar and rotating sleeve; of means for actuating the thrust bar in conformity with the carriage travel of the typewriter, a vertically movable rack bar and mechanism adapting it to transmit rotatable movement to the sleeve and master pinion, and means connected with the operating type levers of the typewriter for transmitting movement to the vertically movable rack bar, substantially as set forth.
10. The combination with a series of indicating wheels, master wheel, sleeve and its pinion; of a tilting frame provided with composite ratchet-toothed spring-pressed pinions, a vertically movable double-sided rack bar operable to engage one or the other of said pinions, a gear engaging the rack bar, and mechanism connected with the key levers of a typewriter for actuating said gear, substantially as set forth.
11. The combination with a series of indicating wheels, master wheel, sleeve and its pinion; of a tilting frame provided with composite ratchet-toothed spring-pressed pinions, a vertically movable double-sided rack bar operable to engage one or the other of said pinions, a gear engaging the rack bar, and mechanism embodying lost motion devices connected with the key levers of a typewriter for actuating said gear, substantially as set forth.
12. The combination with a series of indicating wheels, master wheel, sleeve and its pinion; of a tilting frame provided with composite ratchet-toothed spring-pressed pinions, a vertically movable double-sided rack bar operable to engage one or the other of said pinions, a gear engaging the rack bar, and mechanism comprising a plurality of gears connected with the key levers of a typewriter and embodying locking devices for the inoperative gears, for actuating said gear, substantially as set forth.
13. The combination with a series of indicating wheels, master wheel, sleeve and its pinion; of a tilting frame provided with composite ratchet-toothed spring-pressed pinions, a vertically movable double-sided rack bar, a shaft having a gear engaging the rack bar and provided with a plurality of separately operative gears and clutch mech-

anism, and means for actuating said separately operative gears, substantially as set forth.

14. The combination with a series of indicating wheels, master wheel, sleeve and its pinion; of a tilting frame provided with composite ratchet-toothed spring-pressed pinions, a vertically movable double-sided rack bar, a shaft having a gear engaging the

10 rack bar and provided with a plurality of separately operative gears, clutch mechanism and means for actuating said separately operative gears, substantially as set forth.

15. The combination with the indicating mechanism and the master wheel, sleeve, its pinion, rack shaft, and shifting gear therefor; of mechanism for reversibly actuating the master wheel embodying a vertically 20 movable double-sided rack and a tilting frame pivoted on the sleeve and provided at each side with a two-part ratchet pinion co-operable with the sleeve pinion and the rack, substantially as set forth.

16. The combination with the indicating mechanism and the master wheel, sleeve, its pinion, rack shaft, and shifting gear therefor; of mechanism for reversibly actuating the master wheel embodying a vertically 30 movable double-sided rack and a tilting frame pivoted on the sleeve and provided at each side with a two-part ratchet pinion co-operable with the sleeve pinion and the rack, and spring mechanism maintaining the two-part ratchet pinions in engagement and permitting reversal of one member thereof by the rack without imparting motion to the other, substantially as set forth.

17. The combination with the indicating mechanism and the master wheel, sleeve, its pinion, rack shaft, and shifting gear therefor; of mechanism for reversibly actuating the master wheel embodying a vertically 45 movable double-sided rack and a tilting frame pivoted on the sleeve and provided at each side with a two-part ratchet pinion co-operable with the sleeve pinion and the rack and provided with means for shifting the

50 tilting frame, substantially as set forth.

18. The combination with the indicating mechanism and the master wheel, sleeve, its pinion, rack shaft, and shifting gear therefor; of mechanism for reversibly actuating the master wheel embodying a vertically 55 movable double-sided rack and a tilting frame pivoted on the sleeve and provided at each side with a two-part ratchet pinion co-operable with the sleeve pinion and the rack

60 and provided with a lever for shifting the tilting frame, substantially as set forth.

19. The combination with the indicating mechanism and the master wheel, sleeve, its pinion, rack shaft, and shifting gear therefor; of mechanism for reversibly actuating

the master wheel embodying a vertically movable double-sided rack and a tilting frame pivoted on the sleeve and provided at each side with a two-part ratchet pinion co-operable with the sleeve pinion and the rack 70 and provided with a lever for shifting the tilting frame, said lever having a slotted indicating covering plate, substantially as set forth.

20. The combination with the actuating 75 rack for the master wheel actuating mechanism, of a shaft having a gear engaging the rack and provided with a plurality of lost motion pinions, a shaft having a corresponding series of loosely mounted co-acting gears 80 having lost motion engagement with the shaft, and means for actuating each of said gears separately, substantially as set forth.

21. The combination with the actuating 85 rack for the master wheel actuating mechanism, of a shaft having a gear engaging the rack and provided with a plurality of gears having progressively numbered teeth, a shaft having a series of loosely mounted co-acting gears having lost motion engagement 90 with the shaft, and means for actuating each of said gears separately, substantially as set forth.

22. The combination with the actuating 95 rack for the master wheel actuating mechanism, of a shaft having a gear engaging the rack and provided with a plurality of gears having progressively numbered teeth, a shaft having a series of loosely mounted co-acting gears having a pin and slot engagement 100 with the shaft, and means for actuating each of said gears separately, substantially as set forth.

23. The combination with the actuating 105 rack for the master wheel actuating mechanism, of a shaft having a gear engaging the rack and provided with a plurality of gears having progressively numbered teeth, a shaft having a series of loosely mounted co-acting gears having a pin and slot engagement 110 with the shaft, means for locking the other gears of the shaft, and means for actuating each of said gears separately, substantially as set forth.

24. Means for actuating the master wheel 115 controlling rack consisting in a shaft having a gear engaging the rack and provided with a plurality of mutilated gears mounted on said shaft for lost motion, a shaft provided with a corresponding series of driving gears, and means for actuating the driving gears singly, said gears having portions providing for lost motion of the driving gears, substantially as set forth.

25. Means for actuating the master wheel 125 controlling rack consisting in a shaft having a gear engaging the rack and provided with a plurality of mutilated gears mounted on said shaft for lost motion, a shaft provided with a corresponding series of driving gears 130

- mounted thereon to admit of movement of one gear independent of the others, individual actuating means for each gear, and means for locking the remaining gears 5 against movement, substantially as set forth.
26. Means for actuating the master wheel controlling rack consisting in a shaft having a gear engaging the rack and provided with a plurality of mutilated gears, a shaft 10 provided with a corresponding series of driving gears having locking shoulders, individual actuating mechanism for each driving gear, and cam-actuated pawls adapted to engage the shoulders of the inoperative 15 driving gears, substantially as set forth.
27. Mechanism for locking a series of driving gears for the rack actuating mechanism each provided with an abutment, consisting of a supporting shaft, a cam thereon, 20 a series of pawls, and lever mechanism operatively engaging the cam and pawls, substantially as set forth.
28. Mechanism for locking the rack shaft for the master wheel consisting of an interlocking arm, a partly rotatable shaft, a cam thereon, shaft rotating mechanism, and lever 25 mechanism operatively engaging the cam and said interlocking arm, substantially as set forth.
29. Mechanism for locking the rack shaft for the master wheel and the series of driving gears for the rack actuating mechanism each provided with an abutment, consisting of an interlocking arm for the rack shaft, a 30 supporting shaft for the driving gears, a cam thereon, a series of pawls adapted to engage the gear abutments, and lever mechanism operatively engaging the interlocking arm and said pawls respectively, substantially 35 as set forth.
30. The combination with the intermittently operative shaft for the driving gears, of said gears, each having a slotted hub and pin connection with the shaft, means for 40 actuating each gear separately, and means for preventing reverse movement of the shaft before it has been rotated to its full normal movement, substantially as set forth.
31. The combination with the intermittently operative shaft for the driving gears, of an arc-shaped inclined ratchet faced arm, and a locking arm secured on the shaft having a spring terminal adapted to traverse 45 the inclined faces of the ratchet faced arm, substantially as set forth.
32. Locking mechanism for the driving gear shaft consisting of an arc shaped ratchet faced arm concentric with the shaft 50 and angularly arranged across its longitudinal center, and a locking arm secured to the shaft having a spring terminal adapted to traverse the faces of the ratchet faced arm and to interlock therewith, substantially 55 as set forth.
33. The combination with a driving shaft provided with a series of driving gears, a driven shaft provided with a series of co-acting driven gears, a rack actuating gear, and a clutch; of lever mechanism for the clutch, and a movable cam adapted to actuate the lever mechanism and clutch, substantially as set forth. 70
34. In a typewriter, the combination with computing and indicating mechanism embodying a series of indicating wheels, a master wheel therefor, and mechanism for shifting and rotating the master wheel embodying a rack bar; of individually operative gearing for actuating the rack bar, clutch mechanism adapted to effect operative connection thereof, clutch actuating lever mechanism, and a cam mounted to travel with the carriage of the typewriter adapted to actuate the clutch actuating lever mechanism, substantially as set forth. 75
35. In a typewriter, the combination with two sets of computing and indicating mechanism embodying series of indicating wheels, each having a master wheel and mechanism for shifting and rotating the master wheel embodying a rack bar; of gearing for actuating the rack bars, clutch mechanism adapted to effect operative connection of the gearing to actuate the mechanism for each master wheel, corresponding clutch actuating lever mechanism, and cams mounted to travel with the carriage of the typewriter adapted to actuate each clutch actuating lever mechanism, substantially as set forth. 80
36. In computing and indicating mechanism for a typewriter, the combination with the master wheel and its rack shaft, of a transverse shaft having a gear engaging the rack shaft and a driving pinion, a rack bar 85 engaging the driving pinion and having a latch, and an arm mounted to travel with the carriage of the typewriter adapted to engage the latch to shift the rack bar, substantially as set forth. 90
37. In computing and indicating mechanism for a typewriter, the combination with the master wheel and its rack shaft, of a transverse shaft having a gear engaging the rack shaft and a driving pinion, a rack bar 95 engaging the driving pinion and having a latch, an arm mounted to travel with the carriage of the typewriter adapted to engage the latch to shift the rack bar, and a stationary abutment adapted to effect disconnection of the latch from the arm, substantially as set forth. 100
38. In computing and indicating mechanism for a typewriter, the combination with the master wheel and its rack shaft, of a transverse spring retracted shaft having a gear engaging the rack shaft and a driving pinion, a rack bar engaging the driving pinion, means actuated by the carriage of the typewriter adapted to shift the rack bar, 105 110 115 120 125 130

and means indicating the position of the rack shaft actuating shaft, substantially as set forth.

39. In computing and indicating mechanism for a typewriter, the combination with the master wheel and its rack shaft, of a transverse shaft having a gear engaging the rack shaft, a driving pinion, and an indicator, a rack bar engaging the driving pinion, and means actuated by the carriage of the typewriter adapted to shift the rack bar, substantially as set forth.

40. In computing and indicating mechanism for a typewriter, the combination with the master wheel and its rack shaft, of a

transverse shaft having a gear engaging the rack shaft, a driving pinion, and an indicator, a dial therefor, means limiting the travel of the indicator on the dial, a rack bar engaging the driving pinion, and means actuated by the carriage of the typewriter adapted to shift the rack bar, substantially as set forth.

In testimony whereof I hereunto affix my signature in the presence of two witnesses. 25

ALFRED F. SMITH.
